Ralph W. E. Southworth,
BY
Frank W. Woerner.
ATTORNEY.

UNITED STATES PATENT OFFICE.

RALPH W. E. SOUTHWORTH, OF FLINT, MICHIGAN.

DESIGN FOR AN ADVERTISING-BOOKCASE.

SPECIFICATION forming part of Design No. 30,139, dated February 7, 1899.

Application filed November 19, 1898. Serial No. 696,943. Term of patent 7 years.

To all whom it may concern:

Be it known that I, RALPH W. E. SOUTHWORTH, a citizen of the United States, residing at Flint, in the county of Genesee and State of Michigan, have invented a certain new Design for an Advertising-Bookcase, of which the following is a specification.

The drawing represents a side elevation of my advertising-bookcase embodying my new design.

As indicated in the drawing, the main body of the bookcase is square, the corners being composed of Corinthian columns 5 and 6. Situated between the corner columns are the columns 3 and 4, which columns subdivide the face of the bookcase. Located between

the columns 3 and 4 is a series of shelves 1. The remaining spaces 7 between the corner columns 5 and 6 and the columns 3 and 4 are subdivided into smaller sections, each of which is separate and has a transparent cover.

Having thus described my said invention, what I desire to secure by Letters Patent is—

The design for an advertising-bookcase, as herein shown and described.

In witness whereof I have hereunto set my hand and seal, at Indianapolis, Indiana, this 14th day of November, A. D. 1898.

RALPH W. E. SOUTHWORTH. [L. S.]
